PIVOTABLE WRENCH JAW HAVING QUICK
SLIDABLE ADJUSTMENTCharles M. Smiddy, Fort Covington, N. Y.
Application June 6, 1957, Serial No. 664,052

1 Claim. (Cl. 81—100)

This invention relates to a tool, and more particularly to a wrench.

The object of the invention is to provide a wrench that includes a novel means for locking the movable jaw thereof immobile in its various adjusted positions.

A still further object of the invention is to provide a wrench that includes a stationary jaw and a movable jaw, there being a threaded means which permits the movable jaw to be readily adjusted to any desired position, and wherein means is provided for preventing accidental movement of the movable jaw.

A further object of the invention is to provide a slide wrench which is extremely simple and inexpensive to manufacture.

Other objects and advantages will be apparent during the course of the following description.

In the accompanying drawings forming a part of this application, and in which like numerals are used to designate like parts throughout the same.

Figure 1 is a side elevation of the wrench, with parts broken away and in section.

Figure 2 is a bottom view of the wrench shown in Figure 1.

Figure 3 is a reduced scale perspective view showing the handle.

Figure 4 is a reduced scale perspective view showing the movable member which includes the bar and jaw.

Figure 5 is a reduced scale perspective view of the link.

Figure 6 is a reduced scale perspective view of the pin for connecting the link to the ears of the handle.

Figure 7 is a reduced scale perspective view of the body member which has the interrupted threads thereon.

Referring in detail to the drawings, the numeral 10 indicates the frame or handle which includes a main straight portion 11 which has a head 12 on one end thereof. The head 12 defines a stationary jaw 13 which is provided with a plurality of teeth 14 for engagement with the workpiece or article being gripped or handled.

Extending outwardly from the handle 11 and secured thereto is a pair of spaced parallel ears 9 which are provided with registering openings 15, Figure 3. The pin 16 is adapted to extend through the openings 15 for a purpose to be later described.

There is further provided a movable bar 17 which is provided with a jaw 18 on an end thereof, and the jaw 18 has teeth 19, Figure 1. The bar 17 extends through a slot 20 in the head 12.

Mounted on an end of the bar 17 is a support member 21 which has a pair of spaced parallel lugs 22 extending outwardly therefrom, Figure 4. The lugs 22 are provided with registering apertures, or openings 23. The numeral 24 indicates a body member, Figure 7, and the body member 24 includes a main cylindrical portion 25 which has trunnions 26 and 27 extending outwardly from the ends thereof. A finger piece or knob 28 extends outwardly from the trunnion 27 for use in rotating the body member 24. The main cylindrical portion 25 of the body member 24 is provided with a plurality of threads 29 which are interrupted as at 30 so as to define a longitudinally extending slot or space for a purpose to be later described.

The slide wrench of the present invention further includes a link 31, Figure 5, and the link 31 is provided with an opening 32 in an end thereof for registering with

2

the openings 15 in the ears 9. The link 31 is further provided with a plurality of teeth 33 which are adapted to selectively engage the threads 29 or slot 30, and the link 31 extends into an elongated groove or slot 34 which is formed in the bar 17. A spring member 35 may be arranged in engagement with the bar 17 as shown in Figure 1 for example.

From the foregoing it is apparent that there has been provided a slide wrench, and in use an article or member is adapted to be gripped between the jaws 13 and 18 wherein the teeth 14 and 19 will firmly engage the article which may be a piece of pipe or any other article or member. In order to adjust the movable jaw 18, it is only necessary to manually grip the knob 28 and turn the knob 28 until the clearance or space 30 between the threads 29 coincide with the teeth 33 of the link 31. Then, the bar 17 can be shifted or moved through the slot 20 so that the jaw 18 can be moved towards and away from the jaw 13. After the jaw 18 has been moved to the desired location, the knob 28 is again moved so as to move the body member 24 whereby the threads 29 will move into engagement with the teeth 33 so as to lock the bar 17 and jaw 18 in its adjusted position. As long as the threads 29 are in engagement with the teeth 33, movement of the bar 17 through the slot 20 is prevented. However, when the teeth 33 register with the space 30, then the member 17 can move with respect to the link 31.

The parts can be made of any suitable material and in different shapes or size. When the wrench is being used, the handle 11 is adapted to be gripped in the hand and the article or workpiece being gripped is adapted to be received in the space between the jaws 13 and 18. When the knob 28 is shifted to the proper position, the jaw 18 can be moved either towards or away from the jaw 13. The pin 16 extends through the registering openings 15 and 32 for connecting the link 31 to the ears 9.

The above description of the invention is for illustrative purposes only and it is understood that modifications may be made in the construction within the scope of the following claim.

I claim:

In a wrench, a handle, a pair of spaced parallel ears extending outwardly from said handle and secured thereto, a head arranged on an end of said handle and provided with a slot therein, a bar projecting through said slot, a jaw on one end of said bar, said bar being provided with an elongated groove, a support member on an opposite end of said bar, said support member including a pair of spaced parallel lugs provided with registering openings therein; a link having one end connected to said ears and its other end extending into the groove in said bar, said link being provided with a plurality of teeth thereon; and a body member including a main cylindrical portion interposed between the lugs of said support member, trunnions extending from the ends of said main cylindrical portion and projecting into the openings in said lugs, and a manually operable knob secured to one of said trunnions, threads on the main cylindrical portion of said body member and meshing with said teeth, said threads having longitudinally aligned interrupted portions movable into registry with the teeth on said link for quick slide adjustment of said bar and its jaw.
